RESTAURANT APPARATUS

Truly Warner, New York, N. Y.

Application March 18, 1931. Serial No. 523,453

9 Claims. (Cl. 312—183)

The invention relates to restaurant apparatus. One object of the invention is to provide food to customers at the proper temperature, either hot or cold or both. Another object of the invention is to provide an arrangement of the food that is attractive. Another object of the invention is to keep the food free from dust and to avoid undue handling thereof. Another object of the invention is to provide an attractive and efficient arrangement for a restaurant. Another object of the invention is to insure economy in the running of the restaurant. Another object of the invention is to permit the customer to serve himself with the minimum of effort. Another object of the invention is to keep the restaurant itself at an even temperature. Other objects will be in part obvious or in part pointed out herein-after.

The invention accordingly consists in the features of construction, combinations of elements, and arrangements of parts as will be exemplified in the structure to be hereinafter described, and the scope of the application of which will be indicated in the following claims.

In the accompanying drawings, in which is shown one of various possible embodiments of the features of this invention,

Figure 1 is a plan view of a restaurant arranged and constructed in accordance with my invention.

Figure 2 is a view, partly in front elevation and partly in vertical section, of ovens or heating cabinets,

Figure 3 is a vertical sectional view of an individual oven, showing the interior apparatus in elevation, the plane of the section being perpendicular to the plane of the section in Figure 2,

Figure 4 is a sectional view similar to Figure 3 showing an individual refrigerator or cooling cabinet,

Figure 5 is a plan view of the apparatus in the cabinet of Figure 4, and

Figure 6 is a diagrammatic view illustrating the refrigeration piping.

Similar reference characters refer to similar parts throughout the several views of the drawings.

Referring first to Figure 1, the restaurant may be located in any suitable building, the side walls of which are indicated by the numerals 10, 10. Desirably the front of the restaurant faces on a thoroughfare, and a display section 11 may occupy the front of the restaurant.

So far as certain features of the invention are concerned, the entrance to the restaurant may be of any desirable type, but in order to prevent

draughts, which might under some circumstances interfere with the maintenance of the desired temperature in the food boxes hereinafter to be described, I prefer to seal the restaurant from the outside air by the use, for example, of revolving doors 12 and 13 located at the front and rear of the restaurant respectively. As shown in Figure 1, the revolving door 12 opens into a foyer 14 having swinging doors 15 leading to the street, while the rear door 13 is located in the rear wall 16 of the restaurant.

Assuming now that a customer enters the restaurant through the door 12, he finds before him a table 17, which may be divided into suitable compartments as indicated, and in which he will find 15 napkins, cutlery, spoons, forks and trays, advantageously arranged. The customer is thus guided in the proper direction and may, if desired, be actually restrained from entering the exit passage by means of a turnstile 19, while a railing 20 definitely separates the space around the table 17 from the remainder of the restaurant.

Preferably the customer finds only one avenue of progress into the restaurant which constitutes a passageway 21 bounded on one side by the railing 20 and a railing 22, and on the other side by a row of banks of boxes or cabinets containing food, which row of banks is divided into two parts that are respectively indicated by the numerals 23 and 24. The preferred construction of each of 25 the several boxes or cabinets, their arrangement, and the relation of the set 23 to the set 24 will be described in detail hereinafter. It is noted at this point, however, that each box or cabinet preferably has a transparent front and a transparent front door, so that the customer may see 30 the food contained therein, and desirably also the side walls of each box or cabinet have mirror surfaces so that a customer may see what is in 35 a box considerably removed from his location 40 at that particular moment.

Each of the separate boxes or cabinets composing the set 23 and the set 24 has likewise a rear door openable by an attendant or attendants who have access thereto along a passage 25. The 45 passages 21 and 25 are thus parallel and separated by the food containing cabinets. Customers may be discouraged from entering the passage 25 by providing a locked door 26 at the front end thereof. It should be understood that 50 where in the claims I refer to parallel passages, the case of concentric passages or passages following even irregular but similar courses are included.

Desirably contiguous to the set of cabinets 24 55

and extending normal to the length thereof is a so-called steam table 27 which may be of any usual or desired form and may have a number of compartments or spaces 28 containing hot foods 5 of a fungible nature, that is soups and liquids generally, and such articles as peas, beans and the like, also food which has to be served by an attendant from a larger mass, such as roast beef. On one side of the steam table 27 is a passageway 10 29 bounded by said table and a railing 30 constituting a continuation at right angles of the railing 22. On the other side of the steam table 27 is a space 31 in which stand attendants ready to serve customers. The space 31 is separated from 15 the kitchen 32 by a wall 33, while a door 34 provides access from the kitchen 32 to the passage 25 and the space 31. If desired, additional doors may be provided through the wall 33 to eliminate congestion of the attendants moving to and fro. 20 I will not particularly describe the kitchen, as it may have any desired arrangement and may in fact be located on a different floor or actually in another building, it being representative of a 25 source of supply for the food to be consumed in the restaurant.

The set of boxes or cabinets 23 preferably distinguish from the set of boxes 24. Desirably the boxes of the set 23 are refrigerators, while the 30 boxes of the set 24 are ovens or heated compartments. In order that the heat from the end boxes 24 shall not warm the end refrigerated boxes 23, and that the latter shall not cool the former, a vertical wall of insulation 35 is provided separating the set of boxes 23 from the set of boxes 24.

35 The location of the refrigerator boxes of the set 23 nearer the entrance 12 than the ovens of the set 24 presents several advantages. At all times of the year there are certain customers who desire only a sandwich, a piece of pie, or some 40 article of food which they want cold. Such a customer may obtain a refrigerated article of food from one of the boxes of the set 23 and thereupon leave the passage 21 through the exit 36 between the railings 20 and 22, and as the customer does 45 so a checker, located at a desk 37, gives the customer a slip with the total charge on it. Such a customer, therefore, does not have to walk the entire length of the passage 21 and avoids altogether the passage 29, thus measurably decreasing 50 the congestion in the restaurant. On the other hand, customers who wish hot dishes pass beyond the exit 36 and find them in one of the ovens 24 or at the steam table 27, or both. Such 55 customers have their selections checked by a checker located at a table 38, and thereupon they emerge into the central portion of the restaurant 40 where are located tables and chairs, not shown.

Another advantage of locating the ovens 24 at 60 the far end of the passage 21 is that they are adjacent the steam table 27, thus reducing heat losses. The refrigerators 23 are thus located remote from the steam table 27.

When a customer has finished the meal he finds 65 the only exit from the restaurant is by way of the cashier's table 41 into an exit passage 18 which is separated from the main portion of the restaurant by a railing 42 and at the end of which is the turnstile 19 already referred to.

70 Figure 3 illustrates an individual cabinet or box designated by the number 24a, being a heated cabinet or an oven. Figure 4 illustrates a cabinet or box 23a which is refrigerated. These views serve to point out specific differences in the apparatus and arrangement of the two types of cab-

inets, and in this illustrated embodiment of the invention, where such differences are not pointed out, the two types of cabinets shall be considered to be of the same construction, differing only in the fact that the one type is cooled while the other 5 type is heated. Consequently Figure 5, which specifically shows a plan view of the turntable hereinafter described in a cabinet 23a is to that extent also illustrative of a turntable in a cabinet 24a. Likewise, Figure 2, which illustrates the arrangement of the steam coils, is also illustrative of the arrangement of the refrigerating coils except insofar as certain differences are concerned, which will be duly pointed out.

Referring now to Figure 2, the several cabinets 15 24a of the set 24 are desirably of rectangular parallelopipidal shape and uniform size, and arranged in a row of banks. Referring now to the left-hand side of Figure 2, which illustrates the front of a bank of cabinets 24a, the front thereof is 20 bounded by glass panels 44, 44 set in outside frames 45 and inside frames 46. The panels 44 are desirably made of any desirable heat resistant glass so as to stand the heat produced in the unit 24. A series of doors 47, made also of any 25 desirable heat resistant glass mounted in a suitable frame, are provided, there being one door 47 for each box or cabinet 24a, and the doors swing outwardly and upwardly to open.

The lowermost row of cabinets 24a are located 30 on a platform 48 which is spaced from the floor by a suitable distance so that the customer will not have to stoop down below a certain level in order to reach an article of food. Desirably, as indicated in Figure 1, a shelf 49 extends a slight 35 distance beyond the plane of the fronts of the several cabinets 24a. Beneath the platform 48 and supporting it are front, back and end walls, indicated as a whole by the reference character 50, thus enclosing a comparatively large rectangular parallelopipidal space. In certain cases this space may be utilized, on the one hand to enclose heating apparatus, or in the case of the refrigerating unit to enclose refrigeration apparatus. In this illustrative embodiment of the invention, however, the heating apparatus includes 40 steam pipes emanating from a boiler in the cellar, not shown; while the refrigeration apparatus includes brine pipes emanating from refrigeration apparatus which may be located anywhere desired. 45

Still referring to Figure 2, the unit 24 has a top 51 which desirably includes heat insulating material. Below the horizontal top 51 is a space 52 which, when the unit 24 is in operation, is 55 filled with heated air. Below the space 52 are the top walls 53 of the several banks of cabinets which, as well as the horizontal divisions 54 between successive cabinets, are desirably formed of sheet metal, which may be steel plated with 60 chromium in order to reflect light.

The cabinets 24a have side walls 55 which are also desirably made of sheet metal and plated with a reflecting substance, such as chromium, and polished to a high degree. Considering now 65 a row of cabinets 24a, the right-hand side wall of one cabinet preferably is spaced from the left-hand side wall of the next adjacent cabinet, so as to leave a space 56 extending vertically between successive banks of cabinets in which space 70 are located the steam pipes 57 constituting the heating means for the ovens 24a. Certain advantages follow from the use of sheet metal to form the side walls 55 of the cabinets, among which may be mentioned the rapid heat conduc- 75

tivity thereof, and the absence of double reflection incident to the use of glass mirrors.

The piping 57 is preferably arranged in the space 56 in the form of a continuous ascending zigzag, there being an air relief valve at the top otherwise dead end of the piping, and the bottom of the piping being connected to a steam boiler. Such a system provides for a return of condensed water along the same piping and will not form any water seals. The heat is conveyed to the walls 55 by radiation, convection and conduction, and heated air fills the space 52. Thus each cabinet 24a, except the bottom row, is bounded by a heated medium at the top, at the bottom, and at both sides.

It is desirable to reduce the amount of heat escaping into the restaurant from a cabinet 24a when a customer opens it as much as possible. This is so especially in the summertime, when the restaurant should be kept as cool as possible. Consequently, I preferably provide holes 58 through each of the horizontal partitions 54 and holes 59 through the lowermost partitions 54a and the platform 48, the latter being connected by ducts 60 to piping 61 which leads to a blower 62 located outside of the restaurant. Thus, whenever a front door 47 of a cabinet is opened there will be a slight in-draft.

Referring now to Figure 3, the front door 47 of each cabinet 24a is mounted on a hinge 65 and is provided with a handle 66 near the bottom so that a customer may open the door swinging it upwardly and outwardly. Desirably, any form of spring pressed latch 67 is provided to resiliently hold the door 47 closed. When the door 47 is released, gravity will close it, and a certain spring which will be hereinafter described also assists gravity in this respect.

To the vertical sides of each door 47 and to the adjacent sides of the front walls of the cabinets 24a are fastened movable and stationary elements respectively of segmental shields 68 of the fan type. These shields 68 serve to prevent the escape of heated air upwardly and also act as a limiting stop to prevent excessive movement of the doors 47.

In each cabinet 24a is a turntable 70. This turntable preferably is on an axis located in a vertical plane parallel to the side walls 55, which axis, however, is inclined forwardly a few degrees in said plane. The actual supporting mechanism may comprise a base 71 attached to the bottom 54 of the cabinet and a stud 72 extending into said base. Desirably also ball bearings, not shown, are used to minimize friction.

It may be seen that as the axis of the turntable is inclined with respect to a plane parallel to the front of cabinet 24 (Figure 3) it is subject to actuation by gravitational forces upon being released by an escapement mechanism to be hereinafter described. That is, when an article such as one of plates 110 is removed from its delivery position and the escapement mechanism is released, one side of platform 70 is heavier by reason of supporting more plates than the other (see Figure 5) and accordingly the platform revolves in the direction of the arrow in Figure 5.

The turntable 70 is preferably freely revoluble except for the provision of an escapement mechanism associated with the front door 47, which escapement mechanism will now be described. As shown in Figure 3, a series of pins 73 are attached on the underside of the turntable 70, being located concentrically with respect to the axis of the turntable and at equal angular intervals.

A rod 74 is slidably mounted in the rear of the cabinet 24a and in a bracket 75 under the turntable 70. Near the front end of the rod 74 are a pair of upwardly extending plates 77 and 78, the plate 77 being attached to the far side of the rod 74 as viewed in Figure 3, and the plate 78 being attached to the near side of the rod 74 as so viewed. The width of the rod 74 is equal to or slightly greater than that of the pin 73. In the normal position of the rod 74 the plate 77 lies in the path of revolution of the pins 73, and thus prevents revolution of the turntable 70. When the rod 74 is moved rearwardly, the plate 77 is removed from said path of revolution, and the plate 78 is located in it. These parts constitute an escapement mechanism, allowing the turntable to move the angular distance between successive pins 73 whenever the rod 74 is moved rearwardly and then allowed to come forward again.

Extending rearwardly from the door 47 and in a generally horizontal direction when the door is closed, and located adjacent the hinge 65, is an arm 80. This arm 80 is connected by a link 81 to a bell crank lever 82 which is pivoted at 83 in the cabinet 24a and whose downwardly extending portion rests against a downward extension 84 of the rod 74. Opening of the door 47 results in downward movement of the link 81, which rocks the bell crank lever 82 in a clockwise direction, thus pushing the downward extension 84 of the rod 74 together with the rod rearwardly in the cabinet 24a. This motion is opposed by a spring 86 attached at one end to the support 75 and at the other end to a pin 87 fastened to the rod 74. A stop 88 is provided to prevent excessive movement of the rod 74.

When a customer swings open the door 47, the escapement mechanism described moves one step and allows the turntable 70 to move a very limited distance. The turntable 70 will so move owing to the location thereon of plates having articles of food on one side only as hereinafter more fully described. The customer having withdrawn the plate having the desired article of food, releases the door 47 which thereupon swings closed, and the escapement mechanism moves the second step, thus releasing the turntable 70 for a longer angular movement, bringing the next article in position in front of the door 47. In order that an attendant may have control of the escapement device at all times, the rod 74 projects rearwardly from the cabinet 24a and is provided with a handle 74a whereby the attendant may move it.

Referring now to Figures 4 and 5, so far as the general arrangement thereof is concerned, the several cabinets 23a are the same as the cabinets 24a. Likewise their top, bottom and side walls are desirably of the same construction and arrangement, and vertical spaces are provided between successive banks of cabinets 23a. The parts and spaces so far mentioned, being the same in construction, are given in Figures 4 and 5 the same reference characters as they have in Figures 2 and 3. Instead of steam pipes in the spaces 56, however, refrigeration apparatus is located therein, which may desirably constitute brine carrying pipes 90. Referring now to Figure 6, the arrangement of the brine pipes is diagrammatically shown. The brine is pumped from any suitable source along a pipe 91, whence it is delivered to a supply main 92 to which are connected the lower ends of the several cooling pipes 90 that zigzag upwardly in the spaces 56, as in the case 75

of the steam pipes. The upper ends of all the sets of piping 90 are connected to a connecting main 93, which main 93 is connected to piping 94 filling the space 52 above the top row of boxes 23a. The other end of the piping 94 is connected to a discharge pipe 95 which goes directly downward in any one of the spaces 56 to the entrance port of the circulating pump for the brine system. In describing one particular manner of refrigerating the cabinets 23a, it should be understood that other arrangements of apparatus may be substituted. The particular method of and apparatus for cooling the brine may be of any desired character.

15 Referring again to Figures 4 and 5, each cabinet 23a is provided with a front door 96 comprising a pair of pieces of plate glass 96a and 96b mounted in a suitable frame. The advantage of having a double glass in the door with a space 20 between is that condensation of vapor, which might interfere with vision, is thereby greatly minimized. The door 96 opens downwardly instead of upwardly, in order to retain as much cold air in the cabinet 23a as possible. Each door 96 is hinged at 97, and a latch 98 is preferably provided to resiliently hold it closed. It is likewise connected to its frame on each side by segmental shields 99 of the fan type, which operate as a 25 limiting stop to prevent it being lowered below a certain position and to assist in the prevention of the escape of cold air. In Figure 4 I have shown in dotted lines an illustrative embodiment of the lowermost position of the door 96, which shows it raised above the horizontal. Insomuch as the segmental shields of the fan type 99 guard the sides, cold air in the cabinet 23a is prevented from escaping below the level a. Cold air in a 30 refrigeration cabinet seeks to find a low level and may be considered as analogous to a liquid.

35 40 Connected at one side of the bottom of each door 96 and extending downwardly therefrom inside of each cabinet 23a is an arm 100. This arm 100 lies parallel to the depending portion 84 of the rod 74, which rod has on it the escapement mechanism already described in the case of the cabinets 24a. The cabinet 23a also has in it a turntable 10 having pins 73. As downward movement of the door 96 moves the rod 74 rearwardly against the tension of the spring 86, opening and 45 closing of the door 96 permits the turntable 10 to move an angular distance measured by the distance between the pins 73, the arrangement of the turntable and the escapement mechanism being the same as already described in the case 50 of the cabinets 24a. Likewise, the attendant may operate this escapement mechanism as by means of a handle 74a. Referring to Figure 5, insomuch as the door 96 opens downwardly and not upwardly, an arm 101 is connected to the lower portion 55 of the door 96 at one side thereof, the arm 101 lying in a horizontal plane when the door is closed, but extending to one side so as to avoid the turntable 10. A spring 102 has one end thereof connected to the arm 101 and the other end to the partition 54, and this spring compensates for the weight of the door 96, it being noted that the spring 86 tends to close the door.

60 Referring now to Figures 4 and 3 respectively, each cabinet 23a is provided with a rear door 104, and each cabinet 24a is provided with a rear door 105. Although of slightly different shape, the door 104 is arranged to swing downwardly like the door 96, and the door 105 is arranged to swing upwardly like the door 47. Each of these sets of

doors are provided with segmental shields of the fan type, which are numbered 106 in the case of the doors 104 and 107 in the case of the doors 105. By means of the doors 104 and 105 attendants gain access to the cabinets 23a and 24a respectively. 5 The disposition and location in a horizontal plane of the doors 104 are illustrated in Figure 5, which equally well illustrates the same characteristics of the doors 105, and it is here noted that desirably both of these sets of doors have glass 10 panels and that the rear wall of the cabinets 23a as well as of the cabinets 24a apart from these doors constitutes plate glass 108. Thus the customer may see into each cabinet as well as through it, and on account of the mirror-like sides 15 55, may see into any cabinet from a considerable distance either side thereof.

Referring again to Figure 1, the attendants keep the cabinets 23a and 24a supplied with food from the passage 25. To gain access to any cabinet, the attendant opens the door 104 or 105 as the case may be, and it is noted that each of these doors is so swung as to entrap the heated or the refrigerated air in the respective cabinets. Referring now to Figure 5 as illustrative not only of 25 the refrigerated cabinets 23a but also of the heated cabinets 24a, the attendant places 110 containing articles of food on the turntable 10, there being desirably slight depressions 111 in the turntable located at equal angular intervals and 30 concentrically. The attendant loads the food only at one side of the turntable, either operating the escapement mechanism to move forward successive plates, or reaching in with his hands to 35 place them in the proper positions. The plates being located along one side of the turntable tend to rotate it in a given direction, and as the customers withdraw the plates with food when they are at the lowermost position (see Figures 4 and 5), this tendency will continue so long as one or 40 more articles of food are located on the turntable. By this construction and arrangement there is more than one article of food ready for the customer, and the article withdrawn by the customer is always that which has been the longest time 45 in the cabinet, and therefore heated or cooled to the maximum extent.

The word "cabinet" or "compartment" as used herein signify a complete enclosure or a means enclosing a space completely from the outside 50 thereof.

It will thus be seen that there has been provided by this invention a construction, arrangement and apparatus in which the various objects hereinbefore set forth, together with many thoroughly practical advantages, are successfully 55 achieved.

As many possible embodiments may be made of the above invention and as many changes might be made in the embodiment above set 60 forth, it is to be understood that all matter hereinbefore set forth, or shown in the accompanying drawings, is to be interpreted as illustrative and not in a limiting sense.

I claim:

1. In apparatus of the character described, in combination, a box, means for obtaining access to said box at each end thereof, a turntable axially mounted within said box, the plane of said turntable slanting downwardly toward the 70 front end of said box, said turntable adapted to support articles and convey said articles toward the front end of said box upon rotation, and means for limiting the rotation of said turntable to progressive steps, said last-mentioned means 75

being responsive to the opening and closing of the access means at the front end of said box.

2. In apparatus of the character described, in combination, a box, means for obtaining access to said box at either end thereof, and a turntable axially mounted within said box and adapted to support articles thereon, the plane of said turntable slanting toward one end of said box to facilitate the rotation of said turntable and the movement of said articles toward said end of said box.

3. In apparatus of the character described, in combination, a box, a turntable axially mounted within said box, the plane of said turntable slanting toward the front end of said box, means projecting from said turntable toward the base of said box, means located under said turntable in the path of said last-mentioned means, a door to the front of said box, and means operatively connecting said door to said last-mentioned means whereby said last-mentioned means is momentarily moved out of the path of said projecting means upon the opening and closing of said door.

4. In apparatus of the character described, in combination, a box, a turntable axially mounted within said box, the plane of said turntable slanting toward the front end of said box, studs projecting from said turntable toward the base of said box, an element adapted to move in directions substantially toward and away from the axis of said turntable, a member secured to said element and positioned in the path of said studs when said element is in its forward position, a part secured to said element and positioned in the path of said studs when said element is in its rearward position, said member and said part being sufficiently spaced to permit the escape of one stud during the movement of said element from its rearward position to its forward position, and means for controlling the position of said element.

5. In apparatus of the character described, in combination, a box, a turntable axially mounted within said box, the plane of said turntable slanting toward the front end of said box, studs projecting from said turntable toward the base of said box, an element adapted to move in directions substantially toward and away from the axis of said turntable, a member secured to said element and positioned in the path of said studs when said element is in its forward position, a part secured to said element and positioned in the path of said studs when said element is in its rearward position, said member and said part being sufficiently spaced to permit the escape of one stud during the movement of said element from its rearward position to its forward position, a door at the front end of said box, and means operatively connecting said door to said element whereby said element is moved to its rearward

position when said door is opened and is returned to its forward position when said door is closed.

6. In apparatus of the character described, in combination, a box, a turntable axially mounted within said box, the plane of said turntable slanting toward the front end of said box, studs projecting from said turntable toward the base of said box, an element adapted to move in directions substantially toward and away from the front of said box, a member secured to said element and positioned in the path of said studs when said element is in its forward position, a part secured to said element and positioned in the path of said studs when said element is in its rearward position, said member and said part being sufficiently spaced to permit the escape of one stud during the movement of said element from its rearward position to its forward position, a door at the front end of said box, and means operatively associating said door with said element whereby said element is moved to its rearward position when said door is opened, said element extending through the rear of said box, said means adapted to prevent the effective movement of said element from the rear of said box when said door is in an open position.

7. In apparatus of the class described, in combination, a box, a turntable in said box for supporting articles, said turntable being revoluble in response to gravitational forces upon the removal therefrom of one of said articles, escapement means to permit and impede the rotation of said turntable, and a door at one end of said box operatively connected with said escapement means whereby operation of said door actuates said escapement means.

8. In apparatus of the class described, in combination, a box, a front door to said box, a rear door to said box, a rotatable platform in said box, the plane of said platform being inclined from the horizontal, and means actuatable from the rear of said box to permit step by step loading of said platform through said rear door, said means being operatively connected to said front door whereby the opening and closing of said front door permits said platform to rotate.

9. In apparatus of the class described, in combination, a box, a front door to said box, a rear door to said box, a rotatable platform in said box for supporting articles, said platform being revoluble in response to gravitational forces upon the removal therefrom of one of said articles, and means actuatable from the rear of said box to permit step by step loading of said platform through said rear door, said means being operatively connected to said front door whereby the opening and closing of said front door permits said platform to rotate.

TRULY WARNER. 60
